(57) **CLAIM**

The ornamental design for a light-emitting diode (LED) interior lights fixture, as shown and described.

DESCRIPTION

FIG. 1 is a bottom, front, perspective view of a light-emitting diode (LED) interior lights fixture showing our new design; FIG. 2 is a front elevational view thereof, the rear view being identical to the front view;

FIG. 3 is a left side elevational view thereof, the right side view being identical to the left side view;

FIG. 4 is a top plan view thereof;

FIG. 5 is a bottom plan view thereof;

FIG. 6 is an exploded view thereof;

FIG. 7 is a bottom, front, cross-sectional, perspective view thereof;

FIG. 8 is a view of the encircled area of FIG. 7 on an enlarged scale, illustrating a cross-sectional shape thereof;

FIG. 9 is a bottom, front, cross-sectional, perspective view thereof; and,

FIG. 10 is a view of the encircled area of FIG. 9 on an enlarged scale, illustrating a cross-sectional shape thereof.
